UNITED STATES PATENT OFFICE.

FREDERICK HACHMANN, OF WHITEFISH BAY, WISCONSIN, ASSIGNOR, BY DIRECT AND MESNE ASSIGNMENTS, TO HENRY L. STROHMEYER, OF MILWAUKEE, WISCONSIN, AND THE PRINTING TELEGRAPH AND TYPE WRITER COMPANY, OF ST. PAUL, MINNESOTA.

PRINTING-TELEGRAPH.

SPECIFICATION forming part of Letters Patent No. 630,827, dated August 8, 1899.

Application filed October 27, 1898. Serial No. 694,710. (No model.)

To all whom it may concern:

Be it known that I, FREDERICK HACHMANN, of Whitefish Bay, in the county of Milwaukee and State of Wisconsin, have invented a new and useful Improvement in Printing-Telegraphs, of which the following is a description, reference being had to the accompanying drawings, which are a part of this specification.

10 My invention relates to improvements in printing-telegraph mechanism. The improved mechanism is adapted to be used for transmitting messages telegraphically from one station by continuous conductor or line wire to a distant station and for receiving messages from that distant station. There may be several instruments in the line or circuit. Duplicate instruments are used at the several stations. Synchronous movement of the several instruments is secured by clockwork and by regulation of the instruments by the operators.

15 My invention relates to the improvements in the instrument and related mechanism and devices for transmitting messages by electricity and for receiving messages similarly transmitted and printing them in words and characters.

20 The invention consists of the mechanism and related devices, their parts, and combinations of parts, as herein described and claimed, or their equivalents.

25 In the drawings, Figure 1 is a top plan view of the mechanism and devices embodying my invention. Fig. 2 is a side elevation of the same mechanism and devices shown in Fig. 1. Fig. 3 is a longitudinal vertical section of the mechanism shown in Fig. 1, parts being broken away and other parts omitted for convenience of illustration. Thus on the cylinder in this figure only four pins or teeth are shown, being those on the cylinder in the same diametrical plane and adapted to be contacted by a single key. Fig. 4 is a view of the cylinder. Fig. 5 is a detail of a movement-regulating device and a detail of the paper-feeding mechanism. Fig. 6 is an elevation showing a detail of the paper-feeding mech-

anism, the view being at a right angle to the illustration of the same mechanism in Fig. 5. 50 Figs. 7 and 8 show a paper guard and guides. Fig. 9 illustrates a strip of the paper on which the word "Telegraph" has been printed by my machine.

55 In the drawings, 10 is a base on which the principal operative parts of my mechanism are supported. The frame 11, secured to the base 10, is of such suitable size and form as adapts it for supporting operative parts of the mechanism. A transverse bar 12 and a transverse rod 13, parallel with the bar 12, are secured to and supported on the frame 11 and are electrically insulated therefrom by interposed blocks or pieces of insulating material 14 14'. A number of keys 15, each being preferably 65 a flat metal bar, are pivoted at their rear extremities at little distances apart on the rod 13, that passes transversely through them, the keys at this end being separated from each other conveniently by metal spacing-rings 70 16 on the rod 13 between each two of the keys. For convenience in use each of these keys is provided with a finger-button 17, on which is marked a letter of the alphabet or some figure or character desired in telegraphing and 75 corresponding with the same letters, figures, or characters on the type-wheel hereinafter described.

80 For the purpose of illustrating my invention I have in the drawings herewith shown keys having buttons marked only with the letters of the alphabet; but it should be understood that a greater number of keys can be employed to be marked with figures and characters or that the few keys shown in my 85 drawings could be marked with other characters than letters, the type-wheel being provided with corresponding figures or characters. The front free extremities of these keys 15 enter and are movable in slots forming 90 ways therefor in the bar 12, whereby the keys are guided in their slight movements. Small coiled-wire springs 18, inserted in sockets therefor in the bar 12, are adapted to support the free ends of the keys yieldingly in normal 95 position. An elastic metal finger 19, secured

to each of the keys 15 near its free extremity, projects a little therefrom toward the cylinder hereinafter to be described. The keys 15 are in electric contact with the bar 12 and the rod 13.

Directly below the free extremities of the keys 15 and very near to the fingers 19 a metal cylinder 20 is mounted revolvably in the metal frame 11, transversely thereof. This cylinder is provided with radially-projecting metal pins 21, there being on the cylinder at least as many pins as there are keys 15 and there may be many more pins than keys, it being permissible and convenient to have two or more pins for each key, the pins for each key when more than one is employed being always set in the cylinder in the same plane transverse to the axis of the cylinder, as illustrated in Fig. 3, where four pins are shown so located. Only one pin is, however, ever set in the same radial plane longitudinally of the axis of the cylinder. These pins are adapted severally to be contacted by the finger 19 of the key 15 when the key is depressed by the finger of the operator and the cylinder is revolved.

A type-wheel 22, fixed on the axle of the cylinder 20, has type 23 on its periphery corresponding with the letters on the buttons 17, but of a number corresponding with the pins on the cylinder 20, so that if there are two or more pins on the cylinder 20 set in the same diametrically transverse plane adapted to contact with a single key 15 the type-wheel 22 will have the letter or character of that key repeated two or more times, corresponding in number with the pins in the cylinder adapted to contact with the key of that letter or character. The repetitions of the same letter or character on the type-wheel and the corresponding repetition of pins on the cylinder are used to adapt the machine for rapid work, so that letters or characters that are employed most frequently can be printed when the machine is in operation without waiting for more than a partial revolution of the cylinder.

A means for inking the type 23 consists of an idle-wheel 24, axled on a pin in the free extremity of an arm 25, pivoted at its other extremity on the frame 11. The circumferential outer portion of the wheel 24 is of felt or some analogous material adapted to absorb and hold a suitable ink, and this inking wheel 24 is so arranged as to rest by gravity on the type 23, so that as the type-wheel 22 is revolved the type thereon are inked by contact with the wheel 24.

To cause the cylinder 20 and the type-wheel 22 to rotate continuously and regularly, the cylinder is connected operatively by a train of gears to a drum 26, on which a cord 27, secured at one end thereto, is wound, to the free end of which cord an actuating-weight 28 is attached. The drum 26 is fixed on the shaft 29, and a cog-wheel 30, loose on the shaft, is locked to concurrent revolution with the shaft

in one direction by a pawl 31, pivoted on the spoke of the cog-wheel, the pawl engaging in one direction a ratchet-wheel 32, fixed on the drum 26. The shaft 29 is squared or faced at one end 33 for receiving thereon a crank-handle for winding up the weight-cord on the drum. The cog-wheel 30 meshes with a pinion on shaft 34, which has a cog-wheel 35, that meshes with a pinion on shaft 36, which shaft has a cog-wheel 37, that meshes with a pinion 38 on the axle of the cylinder 20. The cog-wheel and pinions in this train of gears are of such size and so proportioned as to compel the proper rotation of the cylinder 20 by means of the weight 28. The shafts 29, 34, and 36 are journaled in the frame 11.

To regulate the movement of the cylinder 20, a pendulum-escapement 39, pivoted on the frame 11, is so disposed that its pallets alternately engage the teeth of a ratchet-wheel 40, fixed on the axle of the cylinder 20. The depending rod of the escapement is provided with a weight 41, turning by screw-thread thereon, whereby the weight can be raised or lowered and the movements of the pendulum and of the cylinder can thereby be regulated.

To print the letters or characters on the type-wheel 22 severally on a strip of paper 95 passed along in front of the type, I employ a movable hammer 42, mounted loosely in the free extremity of an arm 43, the other extremity of which is fast to the rock-shaft 44, mounted in suitable standards 45. The rock-shaft 44 is provided with a radially-projecting crank-arm 46, connected by a rod 47 to the free extremity of an arm 48, pivoted at its other extremity on the frame in adjustable bearings 49. The arm 48 carries an armature 50, disposed in front of the ends of the cores of the electromagnet 51. The electromagnet 51 is connected by an electric conductor 52, through the binding-post 53, to a battery in the circuit, and the conducting line-wire 54 is connected, through the binding-post 55, to the metallic frame 11. The electromagnet 51 is connected electrically to the bar 12 and therethrough to the keys 15 by the electric conducting-wire 56.

The hammer 42 is tipped or faced with a rubber or analogous slightly yielding and elastic pad 57, that is located directly opposite the periphery of the type-wheel 22 and is adapted to press an interposed strip of paper, as 58, against the opposite type for an instant. The hammer 42 is provided with a rearwardly-extending stem 59, that fits loosely in an aperture therefor through the free extremity of the arm 43. As the arm 43 is thrown upwardly by the armature 50 being attracted to the cores of the electromagnet 51 the free end of the arm 43 is thrown upwardly and contacts with a pin-stop 60, fixed in the frame, and the hammer 42 by its acquired momentum is thrown against the strip of paper 58, pushing it against the type opposite the hammer. The hammer immediately falls back by gravity, and the armature 50 being

released electrically from the electromagnet 51 the free end of the arm 43 also drops to its normal position.

A device for feeding the strip of paper 58 past the type in front of the hammer 42 consists of a drum-like roller 61, preferably of hard rubber, revolvably loose on a stud-pin fixed in a bracket 62, permanently secured on the frame 11, and two toothed disks 63, 10 fixed on a hub 64, revolvably loose on an adjacent stud-pin fixed in the bracket 62. The disks 63 are arranged to be opposite to and enter annular grooves therefor in the drum 61, and these disks 63 are at such distance 15 apart as not to contact with the interposed paper on that central portion of it that is thereafter to receive the impression of the type thereon. A ratchet-wheel 65, fixed on the hub 64, is engaged in one direction by a 20 pin in the finger 66, pivoted at its other extremity in the arm 43. The arrangement of the parts is such that the movement upwardly of the arm 43 carries the finger 66 up, so that the pin thereon engages the next succeeding tooth on the ratchet-wheel 65, and as 25 the arm 43 falls the ratchet-wheel 65 and the disk 63 are rotated limitedly. A spring 67 on the arm 43, bearing against a faced portion of the finger 66, holds the finger yielding 30 up to its work. A spring-pawl 68, secured to a stud-pin on the bracket 62, engages the ratchet-wheel 65 in one direction and prevents movement rearwardly.

A guard 69, located opposite and near the 35 periphery of the type-wheel 22, is adapted to hold the paper at a little distance from the type as it passes the type-wheel and prevent the paper being rubbed against the type; but a slot or aperture 70 at the locality at which 40 the hammer comes up permits the hammer to force the paper against the opposite type. Guides 71, fixed on the guard 69, are adapted for the passage of the strip of paper 58 through them and by which the paper is held 45 to proper position for being struck by the hammer and receiving the imprint of the type thereon.

The drum 44 is axled and supported on the standards 45 by the adjustable pivot pins or 50 axles 72, which are secured releasably in place by lock-nuts 73 turning thereon. It will be understood that in use where duplicate machines of this character are employed at two distant stations connected electrically, the 55 weight 28 being raised by the winding up of its cord on the drum 26 and the cylinder 20 being thereby put in motion and adjusted by the respective operators by preconcerted signals, so that the drums are rotating synchronously on the two instruments, and thereupon either operator may transmit a message by means of the keys 15 to the distant instrument and it will be automatically printed on the strip of paper running past the type-wheel.

65 The specific operation of the various parts of the machine will be understood by the description thereof hereinbefore made.

What I claim as my invention is--

1. In a printing-telegraph, a cylinder and a type-wheel concentric therewith and fixed thereto and mounted in a frame the type-wheel having type thereon some characters of which exist in plurality the cylinder being provided with pins corresponding in number with the type on the wheel, the pins standing for duplicate letters being arranged on the cylinder in the same diametrical plane, and keys one for each letter of the type-wheel arranged movably near to but insulated electrically from the cylinder and so as to be capable of being moved severally into the path of and so as to contact with a pin on the cylinder when the cylinder is revolved.

2. In a printing-telegraph, the combination with a frame and a revoluble cylinder mounted in the frame and provided with a series of radially-projecting pins, of a bar fixed on the frame near to and parallel with the cylinder said bar having guideways extending toward and from the cylinder, and a series of keys pivoted on the frame and movable at their free ends in said bar toward and from the cylinder in said guideways, said bar and said keys being normally electrically insulated from said cylinder.

3. In a printing-telegraph, the combination with a series of pivoted lever-keys, of a key supporting and guide bar arranged transversely of the keys and having slots in which the keys move being guided by the walls of the slots, and having sockets in the bar below the slots, and springs in the sockets adapted to support the keys yieldingly.

4. In a printing-telegraph, the combination with a revoluble type-wheel having type on its periphery, of a hammer-arm adapted to swing toward and from the type-wheel, a stop to limit the movement of the arm toward the type-wheel, and a non-attached hammer loose and reciprocable in the arm adapted to be carried on its seat in the swinging arm toward the type-wheel and on the stopping of the arm at a distance from the type-wheel to move by its momentum against the type on the type-wheel and by gravity to resume position on its seat in the arm.

5. In a printing-telegraph, the combination of a hammer-arm 43 fixed at one extremity on a rock-shaft and provided with an aperture in the free extremity of the arm, the aperture extending in the direction of the movement of the arm, and a hammer mounted on the hammer-arm and having a stem movable in the aperture in the arm and provided with a yielding tip or face.

6. In a printing-telegraph, the combination, of a revoluble wheel having type on its periphery, a rock-shaft, an arm projecting radially from the rock-shaft, a hammer in the free extremity of the arm adapted by the movement of the arm to be thrown against the type, paper-feeding rolls, a finger 66 on said hammer-arm adapted to rotate one of said feed-rolls, an electromagnet, an arna-

ture in front of said electromagnet mounted on a swinging arm, and a rod connecting the free extremity of the swinging armature-arm to a crank on said rock-shaft.

5 7. In a printing-telegraph, the combination with a revolute wheel having type on its periphery, of a strip-guard opposite and near to the periphery of the wheel provided with a medially-disposed aperture therein, guides 10 on the guard at each side respectively of the aperture for receiving and guiding a paper strip, and a hammer adapted to be struck against the strip of paper opposite the aperture in the guard and against a type on the 15 wheel.

8. In a printing-telegraph, the combination of a frame, a power-rotated cylinder having pins in its perimeter, a type-wheel on the axle of the cylinder, a ratchet-wheel on the axle

of the cylinder, and a pendulum-escapement engaging the ratchet-wheel and provided with an adjustable weight on its pendulum.

9. In a printing-telegraph, the combination of a cylinder provided with key-contacting teeth, a type-wheel fixed on the axle of the cylinder, a ratchet-wheel also fixed on the axle of the cylinder, an escapement intermittently engaging and releasing the ratchet-wheel, a weight-actuated drum, and gear interposed between and connecting the drum operatively with the cylinder.

In testimony whereof I affix my signature in presence of two witnesses.

FREDERICK HACHIMANN.
